UNITED STATES PATENT OFFICE.

THEODORE A. PERRY, OF PLYMOUTH, NORTH CAROLINA.

FLOORING-CLAMP.

SPECIFICATION forming part of Letters Patent No. 307,795, dated November 11, 1884.

Application filed September 5, 1884. (No model.)

To all whom it may concern:

Be it known that I, THEODORE A. PERRY, a citizen of the United States, residing at Plymouth, in the county of Washington and State 5 of North Carolina, have invented certain new and useful Improvements in Flooring-Clamps; and I do hereby declare that the following is a full, clear, and exact description of the same, reference being had to the annexed drawings, 10 making a part of this specification, and to the letters and figures of reference marked thereon.

Figure 1 of the drawings is a side elevation of my improved clamp, showing it connected 15 to the sleeper of the floor, the flooring-boards being in section. Fig. 2 is a top plan view thereof; and Fig. 3 an end view, partly in section, taken on line *x x* of Fig. 1.

The present invention has for its object to 20 provide a simple and effective clamp or implement for closing up the joints of flooring-boards, which object I attain by the construction substantially as shown in the drawings and herein described and claimed.

25 In the accompanying drawings, A represents the joist or sleeper of a floor, and B the flooring-boards. Upon the upper face of the joist or sleeper A rests the horizontal portion of an angle-plate, C, cast with a lateral dove- 30 tail extension, *a*, said plate fitting snugly against the upper face and side of the joist or sleeper, as shown more clearly in Fig. 3.

A follower, D, is provided, which is adapted 35 at its front or forward end to press against the outer one of the boards B, to close up the joint with the board next to it, said follower having a dovetail groove, *a*, to fit over the dove-tail extension *a*.

The upper side of the plate C is cast with a 40 lug, *c*, for pivoting thereto a cam-lever, E, provided with a suitable handle, *d*, for operating it.

The inner end of the follower D is cast with a laterally-projecting pin, *e*, (shown in dotted 45 lines, Fig. 2,) which engages with the cam-groove *f*, thus forming a connection between the follower and cam-lever, by which means the follower is forced forward to press against the flooring-board or drawn back without the 50 aid or assistance of a spring, as heretofore.

The inner end of the follower D is formed

with a mortise, *g*, in which the face of the cam-lever E fits and bears, so as to take the strain off the pin *e* of said follower.

To the lug *c* of the angle-plate C is pivoted 55 the upper end of an arm, F, which is of sufficient length to extend some distance below the joist or sleeper A upon one side thereof. The arm F has a sliding block, G, connected to it by a set-screw, *h*, and against the rear 60 side of said arm bears a flat spring, H, which is pivoted to the angle-plate C. When the lever E is brought forward, a shoulder, *i*, upon the inner side thereof will strike that portion of the spring H above its pivotal connection, 65 and by so doing will force the lower end of said spring against the arm F and throw it forward to bring the block G tightly against the under side of the joist or sleeper A, and thus prevent the angle-plate C from sliding 70 backward when closing up the joints in the flooring-boards. After closing up the joints the lever E is pulled back, which releases the spring H from contact with the arm F, when said arm will drop down to a vertical position, 75 and admit of the clamp or implement being removed and connected to the next joist or sleeper.

The block G can be set on the arm F to accommodate it to any thickness of joist or 80 sleeper, and the angle-plate C is preferably provided with spurs *k*, to prevent any lateral motion of the plate upon the joist or sleeper, the spurs embedding themselves in the upper face thereof.

Having now fully described my invention, 85 what I claim as new, and desire to secure by Letters Patent, is—

1. In an implement or clamp for closing up the joints of flooring-boards, an angle-plate 90 adapted to fit over the joist or sleeper, and provided with a lateral dovetail extension, in combination with a cam-lever and a follower connected thereto, said follower having a dovetail groove upon its under side to fit over the 95 dovetail extension of the angle-plate, substantially as and for the purpose set forth.

2. In an implement or clamp for closing up the joints of flooring-boards, an angle-plate having a dovetail extension and a lug upon 100 its upper side or face, in combination with a grooved cam-lever pivoted thereto, and a fol-

lower provided with a pin engaging with the groove, and having a dovetail groove upon its under side, substantially as specified.

3. In an implement or clamp for closing up the joints of flooring-boards, an angle-plate adapted to fit over the joist or sleeper, and provided with a pivoted depending arm carrying an adjustable block, in combination with a grooved cam-lever pivoted to the angle-plate, and a follower provided at its inner end with a laterally-projecting pin engaging with the groove in the lever, substantially as and for the purpose set forth.
4. In an implement or clamp for closing up

the joints, the combination, with a cam-lever 15 and follower connected thereto, of an angle-plate provided with a pivoted depending arm carrying an adjustable block, and a pivoted spring adapted to bear against the arm when the lever is brought forward, substantially as and for the purpose described. 20

In testimony that I claim the above I have hereunto subscribed my name in the presence of two witnesses.

THEODORE A. PERRY.
